UNITED STATES PATENT OFFICE.

RICHARD STEFFEL, OF ORVISTON, PENNSYLVANIA.

WASHBOILER.

1,120,167.

Specification of Letters Patent.

Patented Dec. 8, 1914.

Application filed May 27, 1914. Serial No. 841,279.

To all whom it may concern:

Be it known that I, RICHARD STEFFEL, a subject of the Emperor of Austria-Hungary, residing at Orviston, in the county of 5 Center and State of Pennsylvania, have invented certain new and useful Improvements in Washboilers, of which the following is a specification.

This invention relates to certain new and 10 useful improvements in wash boilers.

An object of the invention is to provide a wash boiler with a removable perforated bottom that will support the clothes or other articles contained therein at a point spaced 15 from the bottom whereby the same may be prevented from burning or becoming otherwise injured should the boiler become empty of water.

A further object of the invention is to 20 provide a wash boiler with means to diffuse the water as it ascends in boiling to more thoroughly cleanse the articles contained therein.

With the above and other objects in view 25 that will appear as the nature of the invention is better understood, the same consists in the novel construction, combination and arrangement of parts to be hereinafter more fully described and then claimed.

30 In the accompanying drawing forming a part of this specification and to which reference is had herein by like characters designating corresponding parts throughout the several views, and in which is shown the 35 preferred embodiment of my invention:

Figure 1 is a vertical sectional view of a boiler embodying the present invention, and Fig. 2 is a horizontal sectional view taken upon line II-II of Fig. 1, with the false 40 bottom removed.

Referring more in detail to the accompanying drawing, the reference numeral 10 designates the side walls of the boiler provided with the bottom 11 having the wall 12 45 upwardly inclined toward the center and carrying a pair of oppositely disposed handles 13. A cover 14 is provided for the boiler 10 and carries the handle 15 by which the same may be removed from the boiler.

50 The cover 14 carries a downwardly projecting flange 16 and a laterally projecting flange 17, the flange 16 snugly engaging the inner upper wall of the boiler, while the flange 17 projects laterally therefrom and

is notched as at 18 for the reception of a 55 locking bolt and nut 19 carried by the handle 13. When the cover is in position as shown in Fig. 1 the boiler is practically rendered air tight or in other words, the steam generated therein is prevented from escap- 60 ing. A blow off valve or cock 20 is carried by the cover 14 and will permit the steam to escape from the boiler should there be an excess generation thereof. At the lower end of the boiler there is provided a drain 65 cock 21 for purposes of emptying the boiler.

Means are provided to diffuse the water in the boiler and consists in providing an annular bead or projection 22 formed on the inner face of the side walls 10 of the boiler, 70 with the face of the bead provided with a plurality of equidistantly spaced arcuate grooves or recesses 23. In order to prevent the clothes or other articles contained within the boiler from being burnt or otherwise injured should the boiler become empty of water, I provide a perforated partition plate 24 equal in diameter to the inner diameter of the boiler and supported on the bead 22. An opening 25 is provided in the center of the perforated partition 24 and is surrounded by an outwardly and downwardly projecting wall 26 apertured as at 75 27 to permit the water to freely circulate therein. 85

In operation, after the articles have been placed upon the perforated partition 24 and the cover 14 sealed to the boiler by the connections 18 and 19, the boiling water rising from the inclined bottom 12 is diffused by 90 passing through the arcuate grooves 23 in the annular bead 22, while the articles contained in the receptacle are spaced from the bottom wall. The diffusion of the water increases the cleansing of the articles within 95 the boiler and renders the device more efficient. Should an excess of steam be generated in the boiler, the valve 20 may be opened to permit the same to escape. By removing the fasteners 19 from the cover 14 100 the cover may be removed from the boiler for access to the contents. The boiler may be emptied of water by the faucet 21.

While I have shown and described the preferred embodiment of my invention, I 105 do not wish to confine myself to the exact details of construction as shown, as various forms and modifications and arrangements

of the parts as shown may be had without departing from the spirit and scope of the invention as claimed.

I claim:—

- 5 1. In a wash boiler, an inwardly directed annular bead carried by the inner face thereof adjacent the bottom, arcuate grooves formed in the bead, and a removably perforated partition supported on said bead.
- 10 2. A wash boiler having a bottom inclined upwardly toward its center, an annular bead formed on the inner face of the boiler adjacent the bottom, curved grooves in the face of the bead, a perforated partition supported on the annular bead at its periphery

and a cone-shaped central support carried by the partition and resting on the inclined bottom of the boiler.

3. A wash boiler having a bottom inclined upwardly, a cover removably secured to the boiler, an annular bead formed on the inner wall of said boiler and having its face grooved to diffuse the water, and a perforated partition supported on the bead.

In testimony whereof I affix my signature 25 in presence of two witnesses.

RICHARD STEFFEL.
